BREAD SLICING MACHINE

William Hoppe, Springfield, Mass., assignor to
 National Bread Wrapping Machine Co., Springfield, Mass., a corporation of Massachusetts

Application July 13, 1938, Serial No. 218,992

20 Claims. (Cl. 146—153)

This invention relates to improvements in bread slicing machines. One object of the invention is to provide a mode of synchronizing the feed of the loaves through the slicing mechanism with the speed of a pusher-type delivery conveyor, this synchronization being preferably automatically controlled. A further object is to improve the manner of mounting the slicing knives. A further object is to provide improved mechanism in various parts of the machine. A further object is to provide an improved form of clutch by which the slicing mechanism may be synchronously connected to an associated wrapping mechanism. Other and further objects will appear from the following description and claims.

This application is a continuation in part of my prior application Serial No. 125,371, filed February 12, 1937.

Referring to the drawings,

Fig. 1 is a side elevation of the machine, partly in longitudinal section.

Fig. 2 is a section on line 2—2 of Fig. 1;

Fig. 3 is a section on line 3—3 of Fig. 1 with certain parts broken away.

Fig. 4 is a detail showing certain clutch mechanism;

Fig. 5 is a section on line 5—5 of Fig. 4, showing the clutch in full lines in released position and in dotted lines in engaged position;

Fig. 6 shows the clutch in the process of releasing itself when the control is shifted;

Fig. 7 is a section on line 7—7 of Fig. 4, with the parts shown in full lines in released and in dotted lines in engaged position;

Fig. 8 is a section on line 8—8 of Fig. 4;

Fig. 9 is a section on line 9—9 of Fig. 4, showing the clutch in released position;

Fig. 10 is a detail of the knife mounting;

Fig. 11 is a detail of one of the knife holding springs;

Fig. 12 is a detail plan of one of the side guides adjacent the termination of the delivery conveyor;

Fig. 13 is a detail plan of one of the side guides adjacent the entrance to the delivery conveyor;

Fig. 14 is a detail showing a method of releasably holding one of the loaf supporting plates;

Fig. 15 is a detail showing a control mechanism for augmenting the feed of the loaves during one cycle, showing the device inactivated by reason of the correct positioning of a loaf;

Fig. 16 is a similar view showing the device activated by the incorrect positioning of a loaf caused by insufficient feeding speed;

Fig. 17 is a similar view showing a device for

decreasing the feeding speed during one cycle when the loaves are being fed too fast;

Fig. 18 is a detail of mechanism shown in Figs. 15 to 17;

Fig. 19 is a detail of mechanism for causing a permanent correction of the loaf feeding speed; and

Fig. 20 is a detail of certain electrical devices used with the mechanism of Fig. 17.

The slicing machine being centered around the 10 reciprocating knife frames the description will be started at that point. The main frame 20, upon which all of the mechanism is eventually supported, has cross pieces 21 at its end, to which longitudinal rails 22 are secured as by bolts 23. 15 These rails form a combined track and sub-frame upon which the knife operating mechanisms are carried and upon which they may be slid out at one end of the main frame after they have been disconnected. Upon the rails four 20 vertical bars 24 are secured as by bolts 25, carrying at their upper ends pins 26 upon which the knife frames slide in a manner to be described. The lower portion of each bar is reduced as at 27 so that if expansion of the knife frames occurs due to the heat of operation, the bars may yield outwardly. This yielding will be confined to the reduced portion of the bars so that their bearing portions will be left straight and since the expansion is small these bearing portions will 30 remain substantially parallel. Screws 28 are threaded into the bars and held by locknuts 29 in adjusted position so that their heads 30 will strike the frame 20 and limit the outward movement of the bars 24, thereby securing centralization of the 35 knife frames and avoiding sidewise oscillation while leaving sufficient room for heat expansion.

The knife frames 31 are preferably made in rectangular form and of hollow construction, and are provided with lugs 32 having a running fit 40 upon the pins 26. The lugs 32 are located well toward the top of the frames, so that a well distributed three-point support is obtained for each frame; the lugs being separated by the width of the frame from each other and by the full height 45 of the frame from the other point of support at the bottom. At their lower central points the frames are detachably connected to the upper ends of rods 33 mounted for vertical reciprocation in a crank case 34 carried by the rails 22. The 50 rods 33 are connected by links 35 with opposite ends of a rocker 36 carried on a pivot shaft 37. This shaft also carries an arm 38 joined by a link 39 with a crank pin 40 on a counterbalancing disk 41 mounted on the end of a shaft 42 likewise 55

mounted in the crank case. At its outer end the shaft 42 carries a pulley 43 connected by a belt 44 with a motor 45. The pivot shaft 46 may be provided with a counterbalance 46 to prevent vibration.

The knives are mounted on their frames by a novel yielding mounting which holds the knives individually under tension. Along the lower cross piece of each knife frame a bar 50 (Fig. 1) is removably dovetailed in place, provided with bifurcated lugs 51 receiving the knives. Cross pins 52 on the knives 53 prevent upward movement of the latter. The upper ends of the knives are yieldably held as is best shown in Figs. 1 and 10. A U-frame 54 is bolted at 55 to the upper cross piece of each knife frame, the lower portion of the U-frame being provided with a rib 56 traversed by slots 57. Through each of these slots passes a spring 58 having a knife-receiving bifurcation 59 at one end and a hole or depression 60 at the other. When the spring is inserted in the slot and engaged at its forked end by the cross pin 52 of a knife, it can be tensioned by a screw 61 threaded through the U-frame and engaging the hole 60, which acts as a positioning means. The tension on the spring can be adjusted by means of the screw 61, the latter being then secured by a lock nut 62. Thereafter the spring can be depressed to permit the knife to be removed without changing this adjustment by means of a lever 63 engageable in a groove 64 in the knife frame and having a heel 65 bearing on the spring as shown in dotted lines in Fig. 10.

The loaves are introduced upon an inclined plate 70 provided with side guides 71. From this plate the loaves pass onto a belt 72 traveling over a supporting plate 73 and mounted on pulleys 74 and 75 carried by shafts 76 and 77 respectively. Shaft 77 is driven by mechanism to be described below. Above the belt 72 is an upper belt 78 mounted on pulleys 79 and 80, suitably journaled for free rotation in a frame 81 carried by a bracket 82. This bracket has a wedge-like enlargement 83 supported on a tapped collar 84 having a flange 85 in engagement with the enlargement so as to prevent rotation of the collar. The collar is threaded onto a screw 86 journaled in the frame and provided with a hand wheel 87 so that the belt 78 can be adjusted in its vertical position. The bracket 82 surrounds the screw 86 loosely, so that the belt 78 rests on the loaves with a pressure due only to the weight of the bracket and the parts carried by it. If a loaf is high or becomes tilted the bracket can be forced up on the screw without exerting undue pressure on the loaf. The bracket is prevented from turning sideways by guide rods 88 (Fig. 2).

During their passage along the belt 72 the loaves are guided by side guides 90 and, after they leave belt 78, by a top guide 91 carried by the bracket 81. As the loaves leave the belt they are received on a plate 92 supported on its ends by brackets 93 having curved portions embracing slabbed-off pins 94 carried by the bars 24. In the position shown in Figs. 1 and 2 the brackets are locked on the pins, but if rotated clockwise the lesser diameter of the slabbed-off pins registers with the openings in the bracket and the latter may be slipped off. To hold the plate in its normal position bolts 95 are slidably mounted in the bars 24, as shown in Fig. 14, so as to fit into holes in the brackets 93. The bolts carry pins 96 (see also Fig. 2) extending through bayonet slots 97 in the bars and engaged by springs 98 to hold the bolts normally in the holes in the bracket.

The plate 92 has fingers 99 (Fig. 1) extending between the knife blades, so that a substantially continuous loaf supporting surface is formed from the belt 72 through the knives. When it is desired to remove the knife frames the plate can be removed as described.

Above the plate 92 are side guides 100 (Fig. 1) pivoted to adjustable brackets 101 by headed pins 102 (Fig. 13) having springs 103 underneath their heads. The guides 100 also carry short dowels 104 adapted to enter holes in the bracket 101 when the guide is in its normal position. When the knife frames are to be removed the guides can be tilted up out of the way by pressing them inwardly sufficiently to free the dowels from their holes. Each guide preferably carries a thin spring plate 105 having a bent portion 106 operating to engage the end of the sliced loaf and prevent undesired motion thereof.

The loaves slide down the plate 92 onto a delivery plate 107 along which they are carried by conveyor mechanism to be described. The delivery plate is mounted on an arm 108 pivoted on a shaft 109 and provided with an arcuate slot 110 through which passes a bolt 111. By this means the elevation of the outer end of the delivery plate can be varied to correspond to that of the infeed of a wrapping machine to which the slicer is coupled. Posts 112 on this arm receive rods 113 and 114 which are held in position by set screws 115. Rods 113 carry the brackets 101 previously referred to, while rods 114 are secured to side guides 116 also fastened to the brackets. At their ends the side guides 116 are provided (Fig. 12) with spring plates 117 having hooked ends 118 preventing excessive inward movement. These spring plates prevent undesired overtravel of the loaves under the impetus given them by the delivery conveyor.

Mounted on sprockets on shaft 109 and on an idle shaft 120 are side chains 121 bearing pushers 122 which extend across the delivery plate 107, passing in the motion of the chains first upwardly through the space between plates 92 and 107, then along plate 107, and finally returning underneath the latter plate. Shaft 109 is driven by a chain 123 passing over sprockets 124, 125, and 126. Sprocket 124 is on shaft 109; sprocket 125 (Figs. 1 and 4) is loosely mounted on a shaft 127 preferably driven from the associated wrapping machine; and sprocket 126 (Figs. 1 and 3) is loosely mounted on a stub shaft 128. The sprocket 125 is driven from the shaft 127 through a clutch mechanism which stops the delivery conveyor in a predetermined position and starts it in timed relation to the wrapping machine. This clutch comprises a sleeve 130 freely mounted on the shaft and pressed towards the left in Fig. 4 by a spring 131 acting against a collar 132 pinned to the shaft. A clutch bar 133 attached to the sleeve extends through a slot 134 in a member 135 pinned to the shaft; and, if the sleeve is displaced to the left from the position shown in Fig. 4, extends into a slot 136 in a member 137 secured to the sprocket 125. The latter slot is made somewhat wider than the clutch bar in order to facilitate its engagement.

The sleeve 130 carries a cam member 140 having an axially inclined radial surface 141 at the bottom of which is a spiral ledge 142. Disposed a short distance radially within the inner terminus of the spiral ledge is a circumferential ledge 143. A cam roll 144 is pivoted at the end of an arm 145 secured against axial movement but free to rotate upon a shaft 146 extending trans-

versely of the machine. Fixed to this shaft is a collar 147, serving to prevent axial movement of the arm in one direction and having a notch 148 one side of which under certain conditions may engage a pin 149 on the arm so as to rock the arm into the dotted line position of Fig. 7. A spring 150 urges the arm in the contrary direction. The shaft 146 is rocked by a handle 151 and is held in either of two positions by a pin 10 152 (Figs. 4 and 9) pressed by a spring 153, recessed in an arm 154 fixed to the shaft, into one of two depressions 155 in a plate secured to the frame.

The clutch is shown in Fig. 5 as in disengaged 15 position. If the handle 151 is rocked to the right in Fig. 7 the edge of notch 148 will be moved against the pin 149, and the arm will be lifted into the dotted line position of Fig. 5, permitting spring 131 to move the bar 133 into the notch 136 as soon as it comes into registry. The roll is held completely out of contact with the cam 140 during continued operation of the machine. It should be noted that since the shaft 127 is driven 20 from the wrapping machine the parts driven by 25 sprocket 125, notably the delivery conveyor, will always be operated in timed relation with that machine.

To disengage the clutch the handle 151 is rocked to the position of Fig. 6, moving the side 30 of notch 148 away from the pin 149 and permitting spring 150 to move the roll 144 towards the axis of shaft 127. If this occurs while the cylindrical part of the cam 140 is underneath the roll the cam will turn under the roll without effect 35 until the cut-away part is encountered. As soon as this occurs the roll will be permitted to move inwardly by the spiral cam 142 and at the same time the sleeve 140 will be forced to the right in Fig. 4 by the pressure of the axially inclined surface 141 against the axially stationary roll 144. As soon as the end of this inclined surface passes the roll the latter rests against the plane end of the cam, and will be pulled inwardly by the spring 150 until it rests against the ledge 40 45 143. Continued rotation finds the roll pressed against the shoulder formed between this ledge and the inner terminus of the spiral surface 142; so that the sleeve 140, which rotates constantly with the wrapping machine, finds no resistance offered by the roll and the cut-away portion 141 produces no effect. The bar 133 will be pulled 50 out of the notch 136 by the axial movement of the sleeve in a predetermined angular position, so chosen that the parts will be stopped in about the 55 position of Fig. 1, with one of the pushers 122 just below its point of emergence between the plates 92 and 107. This permits loaves of bread 60 which have been stopped in the knives to be cleared from the machine by pushing them through manually with another loaf without interference from the pushers. At the same time it 65 will be noted that the pusher 122 at the right in Fig. 1 has passed around the end of the delivery plate, thus having completely delivered a loaf to the cross feed of the wrapping machine. Were a 70 loaf to be arrested half on the plate 107 and half on the wrapping machine feed it would be mashed by the continued operation of the latter, a condition avoided by the construction disclosed. A 75 further advantage is that when the delivery conveyor is stopped no pusher will be in a position to interfere with the removal of plate 92.

The shaft 146 is preferably provided with an arm 156 (Fig. 1) connected by a link 157 with an arm 158 secured to a shaft 159 which may be

provided with a handle 160 (Fig. 3) for convenience in operating the clutch from the other end of the machine. An abutment 161 may be arranged on the arm 158 in position to contact an arm 162 extending from the starting switch 163 5 of motor 45, so that the feed of loaves cannot be started without starting the slicing motor, a condition which would result in jamming and possible breakage.

The feed belt 72 is driven by a variable speed 10 device which can be adjusted in accordance with the width of the loaf to be sliced so that one loaf will be delivered on each passage of the delivery pushers 122. The drive shaft 77 of this feed belt is connected by a chain 165 with a stub shaft 166 15 bearing a large pulley 167. A belt 168 encircles this pulley and also an idle pulley 169, and passes between a pair of cone pulleys 170 (Fig. 3) mounted on the shaft 128 and pressed together by a spring 171. One of the pulleys is connected to 20 the sprocket 126 previously mentioned so as to be driven thereby. The pulley 169 acts to regulate the degree to which the belt is drawn between the cone pulleys and thus acts to regulate the speed of the feed belts. To this end the pulley 169 is 25 mounted on a lever 172 pivoted at 173 to the frame and joined by a link 174 to a rocker 175 pivoted to the frame at 176. The rocker is also connected by a link 177 to a traveler 178 threaded to a shaft 179 journaled in the frame and having 30 hand wheels 180 at its end by which the position of roller 169 can be varied through the linkage described.

It is desirable to have some manner of setting the machine to the approximately correct feeding 35 speed before starting it. For this purpose the traveler 178 has an arm 181 extending through a slot 182 in the frame and bent over at its free end so as to act as an abutment for one side of a test loaf. A fixed abutment 183 is provided for the 40 other side of the loaf. In adjusting the machine a loaf of the size to be sliced is held against the abutment 183, as indicated in dotted lines in Fig. 3, and the arm 181 adjusted by rotating the hand wheels 180 to contact the other side of the loaf. 45 The proportions of the linkages and pulleys described are so chosen that the pulley 169 will be shifted by this setting to give to the feed belt the approximate correct speed for that size of loaf. As loaves are not constant in size some adjustment may be necessary while the machine is running, a matter easily taken care of by rotating the hand wheels 180. 50

Even with an initially accurate setting of the feed belt speed, variation in loaf size will cause 55 the loaves to vary somewhat in the timed relation in which they are delivered to the pushers 122. It is particularly undesirable that the loaves be fed fast enough so that two loaves will be placed between adjacent delivery pushers, and 60 in the endeavor to avoid this the feed is frequently kept sufficiently slow so that a loaf may not be fully on the delivery platform by the time a pusher rises above it. This results in the rear of the loaf riding on a pusher in the manner indicated in Fig. 16. As described in my prior application Serial No. 125,371, mechanism is preferably provided to move such a loaf ahead of the pusher so that it will be seated flat on the delivery table. In the present case such mechanism consists of a bail 193 extending across the path of the loaves and carried by a rocker 194 journaled in standards 187. The rocker is connected by a link 195 to an arm 189 pivoted to the frame at 193 and bearing a cam roll 191. A spring 192 acts 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 on the lever to hold the roll against a cam 193 connected to the sprocket 125. The ball is given a rearward swing high enough to clear a loaf passing under it, and is then swung forwardly far enough to strike the rear of a loaf and move it just in front of the pusher so that it is seated squarely upon the delivery plate.

If the speed is so slow that the loaf overhangs the pusher a considerable amount, the ball may strike the top of the loaf and crush it, or if the spring 192 is lightened sufficiently to prevent this the loaf may not be moved. It is, therefore, desirable in some cases to replace or supplement the manual control with automatic mechanism to regulate the speed so that the feed belt is speeded up whenever a loaf rides on the top of a pusher, thus avoiding the cumulative tendency which would otherwise cause the loaves to lag progressively greater and greater amounts. The correction is conveniently applied to the pulley 75 which drives the feed belts. For this purpose the pulley 75 is driven from the shaft 77 by any conventional free wheeling clutch (not shown) which drives the pulley positively at the speed of the shaft but permits the pulley to be moved ahead of the shaft when desired by other mechanism. A ratchet 195, preferably having undercut teeth for a purpose to be described, is secured to the pulley. An arm 196 is freely pivoted on the shaft and is coupled by a link 197 to an arm 198 pivoted to the frame at 199 and bearing a cam roll 200. The arm is drawn to hold this roll against a cam 201 by a spring 202. Cam 202 is preferably secured to the cam 193, and rotates with the sprocket 125. A pawl 203 is pivoted to arm 196 at 204 (Fig. 18), and is drawn away from the ratchet by the weight of its tail 206 or by a suitable spring. Also freely pivoted upon the shaft 77 is an arm 210 having an abutment 211 adapted to contact with the tail 206 of the pawl when the arm is held by a spring 212 in what might be called its normal position. The end of the arm 210 is formed with a hook 213 which is adapted to be engaged by either of two retainers 214 and 215, which are pivoted at 216 and 217 respectively to stationary brackets 218 and 219. Retainer 214 is normally held in the inactive position of Fig. 15 by a spring 220; while retainer 215 is normally held by its spring 221 in the position shown in Figs. 15 and 16 in which its end will engage the hook 213.

The arm 196 is oscillated continually about the shaft 77, the pawl 203 being normally held out of contact with the ratchet by the pressure of arm 210 against it as shown in Fig. 15. If one of the retainers restrains the arm 210 from following the arm 196, as in Fig. 18, the spring 212 is stretched and the pawl 203 moves away from the arm 210, turning into contact with the ratchet and causing it to rotate. Once in engagement with the ratchet, the undercut teeth of the latter prevent its disengagement until the arm 196 slows down to a speed less than the ratchet. During the major part of the clockwise oscillation of the pawl it is moving at an angular speed higher than the normal speed with which the ratchet is driven, so that it causes an overrunning of the ratchet and the pulley 75 with respect to the shaft 77. At the beginning and end of the stroke the speed is less than the normal speed of the pulley, and the latter is permitted by its free-wheeling connection to travel at its steady normal speed.

Either one of the retainers can be moved out of its normal position by an electromagnet: the

retainer 214 by a magnet 222, and the retainer 215 by a magnet 223. When the magnet 222 is activated the arm 210 will be held from following the pawl throughout the whole of the clockwise oscillation of the pawl, and the ratchet will therefore be given its maximum supplementary advance. If the magnet 223 is activated instead, the arm 210 will be engaged by neither of the retainers and it will travel throughout the stroke of the arm 196 in constant engagement with the pawl. The pawl will, therefore, be held out of engagement with the ratchet and no supplementary motion will be given to the pulley. The constant speed given to the pulley is chosen in this modification so as to give a slight underfeed to the loaves and the effect will be to temporarily reduce the normal feed of the loaves. If neither magnet is energized the arm 210 will travel in contact with the pawl until it is held by the second retainer 215, whereupon the pawl will be permitted to engage the ratchet. A supplementary advance half of its maximum will be given to the pulley in this way, the constant speed of the ratchet being chosen so that the basic advance given to the loaf feeding conveyor by the combined action will be the correct amount necessary to feed the loaves in correct registration with the delivery conveyor.

Magnet 222 is connected by a wire 225 with a contact 226 carried by a pivoted detector 227 normally held by a spring 228 in the elevated position of Fig. 16. Another contactor 229 is fixed in position, and is connected by a wire 230 with a stationary contactor 231. A movable contactor 232 is carried by a detector 233 normally held by a spring 234 in the dotted line position of Fig. 15. This latter contactor 232 is connected by a wire 235 through a current source 236 with a brush 237 in contact with the surface of an insulating disk 238 on the shaft 193. A second brush 239 also in contact with the disk is connected by a wire 240 with the magnet 222. A conducting strip 241 on the disk is of sufficient length to bridge the two brushes once during each cycle, at a time when the detecting action is desired, and thus prevents the energizing of the magnet at any time other than when a loaf is supposed to be over the detector 227. The detector 233 serves a somewhat similar purpose, being lowered to prevent closing of the circuit except when a loaf is in position under it, and thus to prevent activation of the magnet and consequent disruption of the timing of the feeding mechanism during periods when no bread is being fed through the machine.

In Fig. 15 a loaf is shown as being fed in normal position, seated squarely in front of one of the pushers on the conveyor. The detector 227 is held down by the loaf and no correction in the feed is caused. The detector will spring up as soon as the pusher has passed over it, but no activation of the magnet will be caused since the conducting strip 241 will by this time have passed beyond the position where it contacts both brushes. In Fig. 16 a loaf is shown as having been fed to the conveyor somewhat late, so that it is riding on one of the pushers. There is thus a space left underneath the loaf, into which the detector moves. The circuit will therefore be closed, the magnet 222 energized, and the arm 210 will be held back to permit the pawl to give a slight excess feed to the feed pulley, causing subsequent loaves to be advanced in relation to the delivery conveyor.

The mechanism described will serve to correct

a delay in the feeding of the loaves, but since a loaf fed too far ahead will rest on the delivery plate until a pusher catches up with it no difference in position can be detected by the time it reaches the position of Fig. 15. To detect advance feed of the loaves it is necessary to locate a detecting mechanism at a point before the contact of the pusher with the loaves. A mechanical detector may be used as in the preceding case, but it is somewhat more convenient to employ a photoelectric cell, which might also be substituted for the mechanical detector 227.

A light source 242 (Fig. 20) is arranged at one side of the path of the loaves and a photoelectric cell 243 at the other in position to detect a beam of light from the light source through a slot 244 (Fig. 17) in a disk 245 secured to the shaft of the delivery conveyor. Such photoelectric cells are standard commercial products, together with the amplifiers which are controlled by them and which serve to build up their feeble currents to a strength sufficient to operate a magnet. The details of the cell and amplifier are therefore not illustrated, it being sufficient to indicate that the amplifier 246 is connected by wires to the electromagnet 223.

The disk 245 serves the same purpose as the disk 232 previously described, preventing the actuation of the magnet except in correct timing with the mechanism as a whole. If a loaf is fed too far in advance, as in Fig. 17, it will be out of the path of a light ray coming through the slot 244; the preceding loaf being still in a slanting position on plate 92 and hence leaving a V-shaped opening 33 between the two loaves through which the light can pass. The light is received by the photo cell and the resulting activation of the magnet 223 serves in the manner described to decrease the feed of the loaves. If a loaf is in proper position it will block the light rays, and no activation of the magnet results.

The correcting mechanism thus far described changes the feed for one cycle only, leaving the normal feed rate unchanged. It is preferable to combine this with the mechanism about to be described, by which the normal feed rate will be varied with each correction, but to a much smaller degree, so that the mechanism will tend to stabilize itself and eliminate the need of frequent correction. A mechanism for this purpose is shown in Fig. 19, operating on the pulley 169 and changing its position to change the normal feed given to the pulley 75. This comprises two arms 250 and 251 mounted to oscillate upon the shaft 173. Arm 250 is oscillated by a link 252 extending from an eccentric 253 on shaft 171, and arm 251 has an extension 254 connected by a link 255 with an eccentric 256. The eccentrics are set in opposition, so that they oscillate the arms in opposite directions at the same time. Arm 250 bears a pawl 257 and arm 251 a pawl 258, each being held in normally inactive position by a spring 259. A ratchet 260, having double faced teeth, is mounted on a sleeve 261 on the shaft. The sleeve carries a spiral gear 262 meshing with a spiral gear 263 on a shaft 264 held for rotation but against longitudinal movement in an abutment 265 by collars 266. The shaft 264 is threaded at 267 and runs in a nut 268 formed on an arm 269 fast on the arm 172 which carries the pulley 168. Magnets 271 and 272 are mounted adjacent the path of the pawls, the activation of either one causing its pawl to be brought into contact with the ratchet just after the pawl has started its oscillation, the pawl maintaining itself in contact with the ratchet until the

pawl starts its return stroke. One magnet is connected in the circuit of magnet 222, and the other in the circuit of magnet 223, so that when correction in either direction is called for a slight adjustment of pulley 169 will be made in a direction which will tend to reduce the necessity for further correction in the same sense.

I claim:

1. A knife mounting for bread slicing machines comprising a substantially rectangular frame, means on one side of the frame for removably securing one end of each of a plurality of knives thereto, a member having a plurality of spaced apertures located at the other side of the frame, a plurality of flat springs each extending through one of the apertures and having at one end means for interengagement with a knife, and adjustable set screws carried by the frame for exerting knife-tensioning pressure on the other end of each of the springs. 10

2. A knife mounting for bread slicing machines comprising a substantially rectangular frame, means on one side of the frame for removably securing one end of a plurality of knives thereto, a plurality of flat spring rockers each held intermediate their length in the opposite side of the frame and having at one end means for interengagement with a knife, adjustable members carried by the frame for exerting knife-tensioning pressure on the other end of each of the springs, and a ledge adjacent one end of the springs for permitting the flexing of the spring by a pry-bar. 15

3. In a bread slicing machine having a frame, a plurality of spaced knives, and means for conveying loaves to and away from the knives; a plate having fingers extending between the knives to support the loaves while being sliced, end brackets carrying the plate and each having adjacent its lower end a laterally open slot with a narrowed opening, pins carried on the frame in position to be received by each of said slots, the pins being slotted off so as to permit the slotted brackets to pass over them when the plate is tilted but to hold the brackets firmly when the plate is in normal position, and means for releasably holding the upper portions of the brackets to the frame when the plate is in normal position. 30

4. In a bread slicing machine of the type having slicing mechanism, means for feeding loaves through the slicing mechanism, and a pusher-carrying delivery conveyor driven independently of the slicing mechanism; mechanism for controlling the timing of the delivery conveyor with respect to the wrapping or other machine to which the delivery conveyor delivers the sliced loaves comprising a drive shaft driven from said wrapping or other machine, a notched sleeve freely rotatable on the drive shaft and coupled to the delivery conveyor, a sleeve splined to the drive shaft for slidable motion thereon, a dog carried by the splined sleeve and engageable by sliding movement thereof with the notch on the first named sleeve, a spring pressing the splined sleeve in a direction to cause engagement of the dog with the notch, a cam disk carried by the splined sleeve and having a cam surface inclined in the direction of the axis of the shaft, a cam roll, and a mounting for the cam roll restricting it from motion axially of the shaft but permitting it to be moved radially thereof into engagement with said axially inclined cam surface. 50

5. In a bread slicing machine of the type having slicing mechanism, means for feeding loaves through the slicing mechanism, and a pusher-carrying delivery conveyor driven independently 55

of the slicing mechanism; mechanism for controlling the timing of the delivery conveyor with respect to the wrapping or other machine to which the delivery conveyor delivers the sliced loaves 5 comprising a drive shaft driven from said wrapping or other machine, a notched sleeve freely rotatable on the drive shaft and coupled to the delivery conveyor, a sleeve splined to the drive shaft for slideable motion thereon, a dog carried by 10 the splined sleeve and engageable by sliding movement thereof with the notch on the first named sleeve, a spring pressing the splined sleeve in a direction to cause engagement of the dog with the notch, a cam disk carried by the 15 splined sleeve and having a cam surface inclined in the direction of the axis of the shaft, a spiral cam surface, and a circumferential shoulder to which said axially inclined and spiral cam surfaces both lead, a cam roll, and a mounting for 20 the cam roll restricting it from motion axially of the shaft but permitting it to be moved radially thereof into engagement with said axially inclined cam surface.

6. A bread slicing machine having slicing 25 knives, means for driving the slicing knives, a pusher-carrying delivery conveyor, a loaf feeding conveyor frictionally engaging the loaves to feed them in an unbroken series to and through the knives, a drive shaft for said loaf feeding conveyor, a power shaft driven independently of said slicing knives and in timed relation with said delivery conveyor, a pulley on one of said shafts and a pair of spring pressed cone pulleys on the other of said shafts, an idler pulley, a belt 30 surrounding said pulley, cone pulleys, and idler pulley, and means for adjusting the position of the idler pulley.

7. A bread slicing machine having slicing 40 knives, means for driving the slicing knives, a pusher-carrying delivery conveyor, a loaf feeding conveyor frictionally engaging the loaves to feed them in an unbroken series to and through the knives, a drive shaft for said loaf-feeding conveyor, a power shaft driven independently of said 45 slicing knives and in timed relation with said delivery conveyor, a pulley on one of said shafts and a pair of spring pressed cone pulleys on the other of said shafts, an idler pulley, a belt surrounding said pulley, cone pulleys, and idler 50 pulley, a linkage for adjusting the position of the idler pulley, a fixed abutment in an exposed position on the frame, a movable abutment connected to said linkage in position to receive a test loaf between it and the fixed abutment, said linkage being so proportioned that when said abutments 55 are spaced apart a distance equal to the thickness of the test loaf the idler pulley will be set to give a speed to the loaf feeding conveyor which will deliver one sliced loaf to each pusher of the delivery conveyor.

8. In a bread slicing machine, slicing knives, a continuously moving conveyor operating to forward by frictional contact an unbroken series of loaves to and through the knives, a continuously 65 moving conveyor having spaced flights carrying the sliced loaves away from the knives, manually controlled means for varying the speed of the first named conveyor relative to the second to cause the delivery of one loaf for each of said 70 flights, and loaf calipering means connected to said manually controlled means to indicate an initially approximately correct setting of said latter means for a loaf of a particular size.

9. In a bread slicing machine, slicing knives, 75 continuously operating means for feeding loaves

to the knives, means for removing sliced loaves from the knives at periodic intervals, means for detecting misregistration of a sliced loaf with respect to the delivery means, a speed variator for driving the feeding means, and mechanism controlled by said detecting means and connected to the speed variator to vary the speed of the loaf feeding means during its continued movement. 5

10. In a bread slicing machine, slicing knives, 10 means for continuously feeding loaves to the knives, means for removing sliced loaves from the knives at periodic intervals, means for detecting a lagging relation of a sliced loaf with respect to the delivery means, and mechanism controlled by said detecting means for accelerating the continuously operated loaf feeding means. 15

11. In a bread slicing machine, slicing knives, 20 means for feeding loaves to the knives on a downward slant, a downwardly inclined plate receiving sliced loaves from the knives, a substantially horizontal delivery conveyor having spaced flights in position to receive sliced loaves from said plate, means for detecting the presence of a loaf partially riding on one of said flights, means for accelerating the loaf feeding means, and connections between the detecting means and said accelerating means to cause acceleration thereof when a loaf is in a lagging position. 25

12. A bread slicing mechanism comprising slicing 30 knives, a continuously moving loaf feeding conveyor positioned to feed loaves to and through the knives, a pusher-carrying conveyor positioned to receive sliced loaves pushed through the knives by the feeding conveyor, a loaf detector positioned to detect abnormal positioning of a loaf relative 35 to the delivery conveyor, means for varying the speed of operation of the feeding conveyor, and operating connections between the detector and said speed varying means.

13. A bread slicing machine comprising slicing 40 knives, a loaf feeding conveyor positioned to feed loaves in an unbroken series to and through the knives, a pusher-carrying conveyor positioned to receive sliced loaves pushed through the knives by the feeding conveyor, a loaf detector positioned to 45 detect an abnormal lag of a loaf relative to the pushers of the delivery conveyor, means for driving the loaf feeding conveyor a normal amount at each machine cycle, means for causing temporary excess feed of the loaf feeding conveyor, and connections between the detector and the last named means to permit actuation of said last named means only when a loaf is in lagging position. 50

14. A bread slicing machine comprising slicing 55 knives, a loaf feeding conveyor positioned to feed loaves in an unbroken series to and through the knives, a pusher-carrying conveyor positioned to receive sliced loaves pushed through the knives by the feeding conveyor, a loaf detector positioned to detect abnormal advance of a loaf relative to the 60 pushers of the delivery conveyor, means for driving the loaf feeding conveyor a basic amount at each machine cycle, means for causing temporarily diminished feed of the loaf feeding conveyor, and connections between the detector and the last named 65 means to permit actuation of said last named means to diminish the feed only when a loaf is in abnormally advanced position.

15. A bread slicing machine comprising slicing 70 knives, a loaf feeding conveyor positioned to feed loaves in an unbroken series to and through the knives, a pusher-carrying conveyor positioned to receive sliced loaves pushed through the knives by the feeding conveyor, a loaf detector positioned to detect an abnormal lag of a loaf relative to the 75

pushers of the delivery conveyor, a loaf detector positioned to detect abnormal advance of a loaf relative to the pushers of the delivery conveyor, means for driving the loaf feeding conveyor a basic amount at each machine cycle, speed varying means for alternatively increasing or retarding the speed of the loaf feeding conveyor, and means controlled by said two detectors for activating said speed varying means to increase the speed of the loaf feeding conveyor if a loaf has an abnormal lag or to decrease its speed if a loaf has an abnormal advance.

16. In a bread slicing machine of the type having slicing knives, a loaf feeding conveyor positioned to feed loaves in an unbroken series to and through the knives, means for driving the feeding conveyor at a basic speed, and a pusher-carrying conveyor positioned to receive sliced loaves pushed through the knives by the feeding conveyor; the combination with said elements of detecting mechanism for detecting abnormal lag or advance of a loaf, means controlled by said detecting mechanism for augmenting or decreasing the movement of the conveyor a definite amount each time a loaf is abnormally lagging or advanced, and means controlled by said detecting mechanism to decrease the basic speed of the loaf feeding conveyor when a loaf is abnormally advanced and to augment said basic speed when a loaf is abnormally lagging, said changes in the basic speed being of a magnitude to produce a change in the movement of the loaf feeding conveyor at each cycle substantially less than the change produced by said first named detector controlled means.

35 17. In a bread slicing machine, slicing knives, means for pushing an abutting series of loaves through the knives, an endless series of pushers each mounted for movement adjacent said knives to engage the rear of the leading loaf of said abutting series and to carry it away from the knives, said pushers being driven at a rate of speed sufficient to forward at least as many loaves per unit of time as are fed through the knives by the first named pushing means and being of sufficiently low height to permit a pusher to ride under a loaf and carry the loaf along in a tilted position in case the leading loaf of the series is not sufficiently advanced to permit the pusher to contact its rear face, and a pusher movable in timed relation to said pushers but at a higher rate of speed to engage the rear face of said tilted loaf and move it forwardly off from its pusher and to a position in front of the latter.

50 18. In a bread slicing machine, slicing knives,

means for pushing an abutting series of loaves through the knives, an endless series of pushers each mounted for movement adjacent said knives to engage the rear of the leading loaf of said abutting series and to carry it away from the knives, 5 said pushers being driven at a rate of speed sufficient to forward at least as many loaves per unit of time as are fed through the knives by the first named pushing means and being of sufficiently low height to permit a pusher to ride under a loaf 10 and carry the loaf along in a tilted position in case the leading loaf of the series is not sufficiently advanced to permit the pusher to contact its rear face, an oscillatory pusher mounted for movement between a retracted position clear of the 15 path of the loaves and an advanced position intersecting the path of the loaves, and mechanism for holding said oscillatory pusher in its retracted position to permit the passage of each successive loaf and for moving it from its retracted to its 20 advanced position at a speed greater than the speed of said pushers to engage the rear face of a tilted loaf and move it forwardly off from its pusher and to a position in front of the latter.

19. In a bread slicing machine, slicing knives, 25 means for feeding loaves continuously to the knives, means for removing sliced loaves from the knives at periodic intervals, means for detecting misregistration of a sliced loaf with respect to the delivery means, mechanism controlled by said 30 detecting means for accelerating the speed of the continuously operating loaf feeding means, and a pusher contacting the rear of the loaf to forward it sufficiently to overcome its misregistration.

20. A knife frame mounting for bread slicing 35 machines of the reciprocating saw type comprising a main frame, knife frames, a pair of spaced vertical bars of substantially greater length than the height of the knife frames, means rigidly securing the bars at their lower ends only to said 40 frame whereby their upper portions are free to move laterally, interfitting connections between the upper part of the bars and the upper part of the knife frames to permit slidable movement of the knife frames, and means coupled to the lower 45 part of the knife frames for reciprocating the frames, the said vertical bars having adjacent their lower ends, and above said securing means, localized portions of a thickness sufficiently reduced with respect to the body of the bars to permit the expansion of the knife frames by the heat of operation to flex the bars laterally without excessive pressure on the knife frames. 50

WILLIAM HOPPE.
